US00D657377S

(12) **United States Design Patent**
Vance et al.

(10) **Patent No.:** **US D657,377 S**
(45) **Date of Patent:** **** Apr. 10, 2012**

(54) **PORTION OF A DISPLAY SCREEN WITH A USER INTERFACE**

(75) Inventors: **Michael Steffen Vance**, Kenmore, WA (US); **Jasdeep Singh Chugh**, Renton, WA (US); **Feridoon Malekzadeh**, Seattle, WA (US); **Valerie Lynn Goulart**, Seattle, WA (US); **Jupiter Macleod Barton**, Seattle, WA (US); **Jared T. Benson**, Pleasant Hill, CA (US); **Christian Robertson**, Concord, CA (US); **Shilpa R. Shah**, Oakland, CA (US); **Gabriel J. White**, San Francisco, CA (US)

(73) Assignee: **T-Mobile, USA**, Bellevue, WA (US)

(**) Term: **14 Years**

(21) Appl. No.: **29/384,624**

(22) Filed: **Feb. 1, 2011**

Related U.S. Application Data

(63) Continuation of application No. 29/334,512, filed on Mar. 27, 2009, now Pat. No. Des. 631,889.
(51) **LOC (9) Cl.** 32-00
(52) **U.S. Cl.** D14/486
(58) **Field of Classification Search** D14/485-495; 715/700-867

CLAIM

The ornamental design for a portion of a display screen with a user interface, as shown and described.

DESCRIPTION

FIG. 1 is a front view of a user interface for a portion of a display screen showing the claimed design; and,

FIG. 2 is a front view of a user interface for a portion of a display screen showing the claimed design in accordance with a second embodiment.

The portions of the user interface illustrated in broken lines form no part of the claimed design. The outer edge of the portion of the display screen is understood to be congruent with the outer edge of the user interface.

1 Claim, 1 Drawing Sheet
